(57) **CLAIM**

The ornamental design for a battery exchange station as
shown and described.

DESCRIPTION

FIG. 1 is a front, top, and right side perspective view of a
battery exchange station showing our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof; and,

FIG. 7 is a bottom view thereof.

The broken lines are included for the purpose of illustrating
portions of the battery exchange station that form no part of
the claimed design.
